Attorney

UNITED STATES PATENT OFFICE.

WILLIAM C. STROLE, OF DETROIT, MICHIGAN.

ALARM ATTACHMENT FOR PRINTING PRESSES.

Application filed October 8, 1919. Serial No. 329,229.

To all whom it may concern:

Be it known that I, WILLIAM C. STROLE, a citizen of the United States of America, residing at Detroit, in the county of Wayne 5 and State of Michigan, have invented certain new and useful Improvements in Alarm Attachments for Printing Presses, of which the following is a specification, reference being had therein to the accompanying drawings.

In the operation of printing presses of that type having a reciprocable type bed, an automatic feed mechanism, and a magazine for holding paper for the feed mechanism, 15 provision is made so that the type bed is not inked when paper is not in position to properly pass on to the type bed. The paper may not be in position due to a number of causes, mainly, that of the magazine being exhausted 20 or the magazine and the feeding mechanism clogged with paper so that it cannot properly feed onto the type bed. With these magazine printing presses it is customary for an operator to place the same in operation 25 and then attend to other duties, but when the magazine or the feeding mechanism becomes clogged or otherwise rendered inoperative for the purposes for which they are intended, the operator or attendant of 30 the machine does not always immediately discover that the machine is not printing.

The object of my invention is to provide a novel electrical, audible or visible signal 35 which will indicate to the operator or attendant of the printing press that the same requires his attention. The signal is made part of the printing press or machine and is automatically actuated by a controlling member of the printing press. The controlling 40 member is under the influence of the feeding mechanism and when the paper is not in position to be placed on the type bed the signal is operated so that the attendant of the machine may immediately discover 45 why the machine is not properly working and make such adjustments or paper rearrangements so that the press will print in the usual manner.

The mechanical construction entering into 50 this invention will be hereinafter considered and then claimed, and reference will now be had to the drawing, wherein—

Figure 1 is a side elevation of a portion 55 of a printing press provided with a signal in accordance with my invention, and

Fig. 2 is a plan of the same partly broken away.

In order that the operation of the signal may be understood in connection with a conventional form of automatic magazine 60 printing press or machine, I have illustrated a portion of that type of machine which is commonly used in banks or small institutions for printing on small sheets of paper which are automatically fed into position 65 from a magazine in which the paper may be stacked. Such a machine may include a frame work 1 having a reciprocable type bed 2 on which the type or form is placed and this type bed supports a platen or ink working-out plate 3 beneath inking rolls 4 carried by the frame work 1. On the frame work are bearings 5 for an intermittently operated revoluble roller 6 beneath which passes the sheets of paper that are to be 70 printed by contacting with the type bed or form. The roller 6 is supported loosely on an eccentric 7 and at one end of said roller is a pinion 8 meshing with a rack 9 of the type bed 2, so that when the type bed is reciprocated the roller will be revolved. One end of the eccentric 7 has a pinion 10 meshing with a rack 11 adjustable on a slide member 12 and when the slide member is 75 actuated the roller 6 may be raised and lowered relative to the type bed or frame work. For instance, the roller 6 is in a lowered position when holding a piece of paper on the type bed during the forward movement of 80 said type bed, but on the return movement of said type bed the roller is elevated, thus preventing the inked type from contacting with the roller.

The machine also includes a perforated platform 13 in advance of the roller 6 and this platform is adapted to receive sheets of paper from a guide or conveyor 14 in alignment with said platform. Below the platform is a feed roller 15 and above the platform is an adjustable driven feed roller 16 95 journaled in a tiltable frame 17 which is tilted through the medium of the reciprocable type bed to move the feed roller 16 relative to the platform 13, so that a sheet of paper will be fed into position when the 100 type bed is properly located to receive the same. The movable feed roller 16 may be in the form of a plurality of small rollers, as shown in Fig. 2, so as to provide clearance 105 for stop members 18 controlled by the tilt- 110

able frame 17, said stop members entering the perforated platform 13 to hold a sheet of paper in position between the rollers 15 and 16 so that it may be engaged by said rollers and fed between the type bed and the roller 6.

Associated with the stop members 18 is a finger 19 which normally engages a sheet of paper when there is a sheet in position on the platform 13 and the machine is in operative condition, but when a sheet fails to reach the platform 13 then the finger 19 enters the platform and in so doing operates a crank 20 connected to a controlling member 21 extending forward to a cam member 22 slidable at the side of the frame work 1. Associated with the cam member 22 is a trip member 23 adapted to lock the slide member 12, said trip member being in the path of a cam 24 carried by the type bed 2. Besides the slide member 12 abutting the trip member 23 said slide member is adapted to have its opposite end 25 engaged by the rear end of the type bed and said type bed, through the medium of the slide member 12 controls the raising and lowering of the roller 6.

All of the above mechanism is of a conventional form and it is thought unnecessary to enter into a detailed description of the exact operation of the mechanism, other than to state that the controlling member 21 will be operated when sheets of paper are not in position to pass through the printing press. Operation of the controlling member 21 means a reciprocable movement thereof, so I provide said member with a contact member 26 adapted to engage a stationary or yieldable contact member 27 supported from a block of insulation 28 on the frame work 1. The yieldable contact member 27 is

connected by a wire 29 to an ordinary switch 30 and said switch is in circuit with the battery or cells 31 constituting a suitable source of electrical energy. The battery 31 is connected by a wire 32 to an audible signal 33, as an electric bell, and said signal is connected by a wire 34 to the contact member 26, so that when the switch 30 is closed and the members 26 and 27 contact there is a closed circuit which causes the signal to be operated and thus indicate to the attendant of the machine that paper is not properly feeding or the magazine has become clogged.

What I claim is:—

In a printing press having a paper feeding device with a feeler finger normally resting on the paper and adapted to be released by the absence of paper:—means adapted to provide a signal when the feeler finger is released, said means comprising a normally open contact device in an electric signal circuit, said contact device having its circuit maintained open by the feeler finger resting on the paper and which circuit is closed by the feeler finger being released by the absence of the paper, a controlling member connected to and reciprocated by the feeler finger, a trip member actuated by said controlling member, a contact member adapted to be engaged by the contact member of said controlling member to complete the electric signal circuit, said trip member holding the contact member of said controlling member in engagement with said resilient contact member.

In testimony whereof I affix my signature in the presence of two witnesses.

WILLIAM C. STROLE.
